1

Genus and species: *Citrus limon*.

Variety denomination: '7 ELS C3'.

BACKGROUND AND SUMMARY OF THE VARIETY

The new lemon variety '7 ELS C3' originated as an induced mutation of 'Eureka' lemon (not patented). Gamma irradiation from a Gammacell 200 (60C) source was applied to bud sticks of 'Eureka' in 1998 at Emerald, Queensland, Australia. The irradiated bud sticks were budded onto 'Carriizo' rootstock (not patented) in June 1998 at Bundaberg, Queensland, Australia, and the trees that survived were field planted at Bundaberg in 1999. The selection now known as '7 ELS C3' was identified as showing consistently fewer seeds than the parent variety, with no significant reduction in fruit size. A comparative trial was planted in 2003, using '7 ELS C3' budwood on 'Benton' (not patented) rootstock. Successive generations have consistently shown few seeds and have reproduced true to type.

'7 ELS C3' is a new and distinct lemon tree notable for its fruit, which produces consistently low numbers of seeds. Table 1 shows a comparison of '7 ELS C3' lemon to 'Eureka' and other similar (unpatented) varieties.

TABLE 1

Comparison of '7 ELS C3' to Known Varieties			
Characteristic	'7 ELS C3'	'3 ELS 0'	'Eureka'
Seed quantity	Few to medium	Absent to few	Many
Mean fruit length (mm)	84.24	74.56	84.76
Mean fruit diameter (mm)	60.32	57.16	62.84

(57) **ABSTRACT**

'7 ELS C3' is a new and distinct lemon tree notable for its high quality seedless fruit.

4 Drawing Sheets**2****TABLE 1-continued**

Comparison of '7 ELS C3' to Known Varieties			
Characteristic	'7 ELS C3'	'3 ELS 0'	'Eureka'
Fruit length/diameter ratio	1.40	1.31	1.35
Rind thickness (mm)	4.76	4.48	5.24

10 BRIEF DESCRIPTION OF THE PHOTOGRAPHS

FIG. 1 shows whole and sectioned fruit of '7 ELS C3' lemon and other varieties;

FIG. 2 shows a '7 ELS C3' lemon tree;

FIG. 3 shows the trunk, branches and leaves of a '7 ELS C3' lemon tree; and

FIG. 4 shows the fruit and leaves of a '7 ELS C3' lemon tree.

The tree shown in FIGS. 2, 3 and 4 is an eleven year old tree planted in 2003. Because lighting conditions can affect the colors shown in photographic illustrations, color characteristics of this new variety should be determined with reference to the observations described herein, rather than from the illustrations alone.

25 DETAILED BOTANICAL DESCRIPTION

The following detailed botanical description is based on observations of trees and fruit of '7 ELS C3', budded to 'Benton' rootstock (not patented) and planted in 2003. 30 Observations were recorded and photographs taken during the 2006 and 2014 growing seasons at Mundubbera, Queensland, Australia. It should be understood that the characteristics described will vary somewhat depending upon cultural practices and climatic conditions, and can vary with location

and season. Quantified measurements are expressed as an average of measurements taken from a number of individual plants of the new variety. The measurements of any individual plant, or any group of plants, of the new variety may vary from the stated average. Colors are described with reference to The Royal Horticultural Society Colour Chart (5th edition, 2007).

Tree:

<i>Vigor.</i> —Vigorous.	10	<i>Flowering habit.</i> —More than once in a season; up to 7 flowerings observed.
<i>Density of canopy.</i> —Dense.		<i>Date of first fruitlet fall.</i> —November.
<i>Habit.</i> —Upright spreading.		<i>Pedicel length.</i> —5 mm.
<i>Height.</i> —4 m.		<i>Pedicel diameter.</i> —1.9 mm.
<i>Spread.</i> —3 m.		<i>Pedicel color.</i> —Yellow-green 151C.
<i>Trunk diameter (at 30 cm above graft).</i> —150 mm.	15	<i>Pistil quantity per flower.</i> —1.
<i>Bark texture.</i> —Smooth.		<i>Pistil length.</i> —11.9 mm.
<i>Bark color.</i> —Greyed-orange 163D, greyed-purple N187A.		<i>Pistil color.</i> —Orange 26A, yellow 9A, yellow-green 144A.
<i>Lenticel size.</i> —1 mm.		<i>Anther quantity per flower.</i> —1.
<i>Lenticel color.</i> —Greyed-purple N187A.	20	<i>Anther length.</i> —3 mm.
<i>Lenticel quantity.</i> —Many, 2 to 4 per cm ² .		<i>Anther color.</i> —Orange 26A.
<i>Tendency toward alternate bearing.</i> —None.		<i>Stigma quantity per flower.</i> —1.
<i>Winter hardiness.</i> —Same as 'Eureka', performs well in USDA hardiness zones 9 and 10.		<i>Stigma length.</i> —2.1 mm.
<i>Chilling requirement.</i> —Same as 'Eureka', no chilling requirement.	25	<i>Stigma color.</i> —Yellow 9A.
<i>Drought tolerance.</i> —Same as 'Eureka', tolerant.		<i>Style quantity per flower.</i> —1.
Branch (fruiting branch located about 1 m above graft union):		<i>Style length.</i> —9.8 mm.
<i>Length.</i> —80 cm.	30	<i>Style color.</i> —Yellow 1B.
<i>Diameter.</i> —6 cm.		<i>Ovary quantity per flower.</i> —1.
<i>Crotch angle.</i> —Approximately 30 degrees.		<i>Ovary length.</i> —4.7 mm.
<i>Bark color.</i> —Greyed-orange 163D, greyed-purple N187A.		<i>Ovary diameter.</i> —3 mm.
<i>Bark texture.</i> —Smooth.	35	<i>Ovary color.</i> —Yellow-green 144A.
<i>Thorns.</i> —Present.		Leaves:
<i>Thorn length.</i> —Very short, 5 mm or less.		<i>Length.</i> —105 mm.
Current year shoot:		<i>Width.</i> —58.7 mm.
<i>Length.</i> —80 cm.		<i>Length/width ratio.</i> —1.78.
<i>Color.</i> —Green 140A.	40	<i>Blade margin.</i> —Crenate.
Blossoms:		<i>Leaf shape.</i> —Oval, weak concave.
<i>Bud shape.</i> —Oval.		<i>Apex shape.</i> —Acute.
<i>Bud length.</i> —2.2 mm.		<i>Base shape.</i> —Cuneate.
<i>Bud diameter.</i> —1 mm.		<i>Color of upper surface.</i> —Green 143B.
<i>Bud color.</i> —Yellow-green 144A.	45	<i>Color of lower surface.</i> —Yellow-green 145A.
<i>Quantity of blossoms per cluster.</i> —4 to 7.		<i>Anthocyanin coloration in young leaf.</i> —Weak, less intense than 'Eureka'.
<i>Blossom diameter.</i> —23 mm.		<i>Leaf texture (upper surface).</i> —Smooth.
<i>Blossom depth.</i> —19 mm.		<i>Petiole length.</i> —12.3 mm.
<i>Pollen.</i> —None.		<i>Petiole diameter.</i> —2.5 mm.
<i>Sepal length.</i> —4.2 mm.	50	<i>Petiole color.</i> —Yellow-green N144D.
<i>Sepal width.</i> —4.4 mm.		<i>Wings.</i> —None.
<i>Sepal shape.</i> —Arched.		Fruit:
<i>Sepal margin.</i> —Smooth.		<i>Quantity per cluster.</i> —4.
<i>Sepal color.</i> —Upper surface — Yellow 2B.		<i>Axial diameter.</i> —84.24 mm.
<i>Sepal color.</i> —Lower surface — Yellow 3B.		<i>Apical diameter.</i> —60.32 mm.
<i>Quantity of petals per flower.</i> —6.	55	<i>Weight.</i> —159 g.
<i>Petal shape.</i> —Elongated arch.		<i>General shape in profile.</i> —Oval.
<i>Petal apex.</i> —Rounded to acute.		<i>Position of maximum diameter.</i> —Middle of fruit.
<i>Petal margin.</i> —Smooth.		<i>Navel.</i> —None.
<i>Petal length.</i> —19 mm.	60	<i>Neck.</i> —Present, very short.
<i>Petal width.</i> —5.2 mm.		<i>Nipple.</i> —Present, weak to medium prominence.
<i>Petal color.</i> —Upper surface — White NN155D.		<i>Rind color.</i> —Green 140B.
<i>Petal color.</i> —Lower surface — White NN155D, violet 84D.		<i>Glossiness.</i> —Weak.
<i>Date of first bloom.</i> —Late August.	65	<i>Oil glands per cm².</i> —About 40.
<i>Date of full bloom.</i> —Early September.		<i>Oil gland diameter.</i> —1 mm.
		<i>Oiliness.</i> —Oily.
		<i>Rind thickness.</i> —4.7 mm.
		<i>Ease of peeling.</i> —Difficult.
		<i>Rind texture.</i> —Smooth.
		<i>Albedo thickness.</i> —3 mm.
		<i>Albedo color.</i> —Yellow 2C.
		<i>Quantity of fruit segments per fruit.</i> —8.2 (average of 25 fruit).
		<i>Toughness of segment membrane.</i> —Moderate.
		<i>Juice sac length.</i> —9 mm.
		<i>Juice sac shape.</i> —Cylinder.

US PP29,440 P3

5

Juice sac length to width ratio.—9:1.5.

Juice sac color.—Yellow 2C.

Flesh color.—Yellow 2C.

Juice soluble solids (° brix).—7.5.

Relative harvest maturity.—Early.

Harvest window (date range).—January through December.

Seeds present.—None or very few.

Stem length.—20 mm.

Stem diameter.—4 mm.

Stem color.—Yellow-green 144B.

6

Parthenocarpy.—Absent.

Diseases and pests.—No distinguishing resistance or susceptibility noted.

Harvest yield: 50 to 100 tons per hectare.

⁵ Market use: Fresh.

Keeping quality: Same as 'Eureka'.

Shipping quality: Same as 'Eureka'.

The invention claimed is:

1. A new and distinct variety of lemon tree, substantially 10 as illustrated and described herein.
